TUFTING MACHINE

Clarence M. Jones, Calhoun, Ga.

Application March 1, 1937, Serial No. 128,306

9 Claims. (Cl. 112—79)

This invention relates to improvements in tufting machines.

An object of the invention is to provide an improved looping and shearing device.

5 Another object is to provide a device of the above nature in which operation of the shearing mechanism immediately precedes actuation of the looping means and in which movements of the looper are short and rapid.

10 Another object is to provide a device of the above character in which the parts are simple, strong and durable.

A further object is to provide a device of the above nature in which storage of successive loops 15 on looping member is eliminated.

A still further object is to provide a device of the above nature which may be operated at high speed.

Other objects and advantages of the invention 20 will become evident during the course of the following description in conjunction with the accompanying drawings, in which

Figure 1 is an enlarged perspective view of the looping and shearing mechanism.

25 Figure 2 is an end view of a machine incorporating the invention.

Figure 3 is a vertical section view showing the rocker-shaft connections.

Figure 4 is a side view of the device partly in 30 section.

Figure 5 is a fragmental view showing a loop being sheared.

Figure 6 is a similar view showing the looper intercepting a loop.

35 Figure 7 is a similar view showing the shear opened to receive the loop.

Figure 8 is a similar view showing the looper retracted.

Referring to Figure 1, the numeral 10 indicates 40 a rear plate on which are disposed a lower guide rail 12 and an upper guide rail 11. A rectangular bar 13 is slidably guided between the rails 11 and 12, and is retained in place by a cover plate 14, the cover plate, rails and guide plate 45 being secured to an angle bracket 15 by means of bolts 16, the bracket being vertically slotted as at 16a, Fig. 4, to receive the bolts. A vertical ridge or key 17 on the bracket 15 engages a groove 18 in the rear plate 10, thus serving to position the latter and its attached parts accurately and rigidly in place.

The bar 13 has an upright portion 19 to which is secured a flat triangular looper body 20 having a horizontally extending shank 21 which terminates in a downwardly directed hook 22. The

lower edge 23 of the shank 21 is ground to a shear edge. A shear blade 24 is pivotally mounted at 24a on the looper body 20 so as to be cooperative with the shear edge 23. The forward end 25 of the shear blade 24 is blunted, and the length 5 of the blade is such that when it is rocked upward into closed position the blunt end 25 is located closely adjacent the rear slope of the hook 22. A spring washer 26 may be provided under the head of the pivot 24a to urge the shear blade 10 15 24 into proper shearing relation with the edge 23.

The shear blade 24 has a downwardly extending arm 27 to which is pivoted at 28 one end of a transverse rod 29. The other end of the rod 29, as shown in Figure 2, is secured to an eye 30 15 which is pivoted to a lever 31 on the end of a rocker shaft 32 journaled in the frame 33 of the machine, the bracket 15 being secured to the bottom of frame 33 as shown in Figure 4 by bolts 35 extending through slotted holes 36, Figs. 4 and 1. 20 The rocker shaft 32 is operated by means of a second lever 37, Figure 3, which is linked through a connecting rod 38 to an eccentric 39 on the main shaft 40 of the machine.

Referring to Figures 1 and 2, it will be seen 25 that the cover plate 14 has therein an opening 41 through which is exposed a relatively short slot 42 in the rectangular bar 13. The pivot 28 of the shear arm 27 extends through the opening 41 and engages the slot 42, but is adapted to swing freely 30 between the left and right ends 43 and 44 of the latter. The lever 31 and rod 29 are adapted to impart to the pivot 28 a motion longer than the latter's possible swing in the slot 42. As a result, when the rod 29 starts a stroke to the right, it first 35 swings the shear 24 about the pivot 24a into complete shearing engagement with the shank edge 23, then as the pivot 28 encounters the right end 44 of the slot 42, continued motion of the rod 29 moves the entire combination of bar 13, looper 40 20 and shear 24 to the right as a unit until the counterclockwise motion of the rocking lever 31, Fig. 2, is completed. Similarly, motion of the lever 31 and rod 29 to the left first swings the shear blade 24 clockwise into open position while 45 the bar 13 and looper 20 remain stationary, then as the pivot 28 encounters the left end 43 of the slot 42 the bar, looper and shear are moved to the left as a unit. Thus the first part of each stroke of the rod 29 closes or opens the shear while 50 the second part slides the shear and looper assembly bodily forward or backward. As the engagement of the pivot 28 with either end of the slot 42 occurs near the midpoint of the motion imparted to the rocker shaft 32 and lever 31 by the ec- 55

centric 39, Fig. 3, the start of the looper assembly's sliding motion occurs suddenly and at relatively high speed. Sufficient friction is provided between the bar 13 and its guides to prevent over-run of the bar in either direction and to ensure operation of the shear before sliding can occur.

The machine comprises the usual head 45, Figures 2 and 4, having a vertically reciprocating plunger 46 carrying a needle 47 having an eye 48 near the point thereof. A tension device of any suitable type, such as a spiral spring 49 on the top of plunger 46, is provided to take up slack and set up proper tension in the yarn 50 threaded through the eye 48 of the needle 47 in the usual manner, the needle being adapted to reciprocate through a throat plate 51. The machine also comprises feeding shoes 52, cooperative with the usual presser foot 53 and adapted to feed a fabric 56 to the left between downward strokes of the needle 47, the feeding shoes being operable from two rocker shafts 54 and 55 in a manner well known in the art and therefore requiring no further description herein.

The operation of the device is as follows:

25 Referring to Figures 5, 6, 7, and 8, it will be seen that when the needle 47 is driven downward through the fabric 56 it travels past the hook 22, reaches the bottom of its stroke and in starting its return stroke forms a loop 57 of the yarn 30 50. Meanwhile the lever 31 and rod 29 have been drawing the pivot 28 to the right to swing the shear 24 counter-clockwise and sever any previous loop which may be on the shank 21, and thereby form a pair of tufts. As the loop 57 is formed by the upward motion of the needle 47, the pivot 28, having closed the shear, encounters the right end 44 of the slot 42, and the continued motion of the pivot moves the entire looper and shear combination sharply forward, thrusting the 40 hook 22 through the loop 57. The continued upward movement of the needle 47 draws the loop 57 into the V-notch formed by the rear inclined edge of the hook 22 and the blunt nose 26 of the shear blade.

45 As the rocker shaft 32 terminates its counter-clockwise motion and starts its return or clockwise swing the rod 29 and pivot 28 first swing open the shear. At the same time the feeding shoes 52 move the fabric 56 to the left and this 50 motion together with the upward tension of the yarn 50 slides the loop 57 up the inclined edge of the hook 22 and onto the shank 21 above the edge of the shear blade, the looper remaining stationary during this operation. As the shear 55 comes to full open position the pivot 28 engages the left end 43 of the slot 42 and thereafter moves the looper and shear bodily to the left, retracting the hook 22 and the loop thereon to allow the needle 47 to form the next loop. The 60 shear is again closed to shear the loop on shank 21 and the hook 22 is immediately thrust forward to intercept the newly formed loop.

65 From the foregoing description it is evident that the shank 21 holds only one loop at a time, thus avoiding any possibility of crowding and interference such as may occur in machines requiring the simultaneous storage of two or more loops. The shearing of each loop is followed almost instantaneously by the interception of the 70 next, thus further avoiding any possible displacement or tangling of the yarn. The fact that the looper remains stationary at the forward end of its stroke promotes accurate location of the loop on the hook. Similarly, the fact of the looper's 75 stationary period at the rear end of its travel

permits its rear location to be quite near the needle. The intermittent motion of the looper thus occurs over a comparatively short distance, and this fact together with the close and accurate inter-relation of the parts with the needle, and elimination of possible tangling permits the machine to be operated satisfactorily at high speed. As the looper itself is in effect operated through the shear, it is impossible for these parts to get out of proper timing. The shearing of each loop prior to the interception of the next makes it unnecessary at the end of a run to operate the machine further in order to shear any stored loops.

The horizontally slotted holes 36 in the bracket 15 allow the entire mechanism to be moved longitudinally on the frame 33 to adjust the path of the hook 22 nearer to or farther from the path of the needle 47. Similarly, the slotted holes 16a in the bracket 15 provide for vertical adjustment by moving the rear plate 10 upward or downward along the key 17. The eye 38 may be threaded to the rod 29, thus also providing for crosswise adjustment of the mechanism with regard to the needle. It will be seen that the parts 25 are few, simple and rugged, making the device adaptable to long and rapid operation without trouble or undue wear.

While the invention has been described in preferred form, it is not limited to the exact structure illustrated, as various modifications may be made without departing from the scope of the appended claims.

What is claimed is:

1. In a tufting machine, in combination, means 35 to support a fabric, a needle reciprocable through said support to carry a yarn through said fabric, said needle being adapted to form successive loops under said fabric, a looper movably supported adjacent said needle and comprising a hook adapted 40 to individually receive said loops, a shear member pivotally mounted on said looper and cooperative therewith to individually shear said loops, a second pivot in said shear, stops on said looper adapted to be engaged by said second pivot to 45 limit the arc of swing of said second pivot and said shear in both directions and means connected to said second pivot and movable in one direction to initially open said shear and to move said second pivot against one of said stops and to subsequently move said first stop and said shear and looper as a unit whereby said looper may be withdrawn from said needle while carrying one loop and operable in the other direction to initially 50 close said shear and to move said second pivot against said other stop whereby said loop may be severed and to subsequently advance said second stop and said shear and looper as a unit whereby said looper may intercept a second loop.

2. In the tufting device cooperative with a 60 reciprocating needle adapted to carry yarn through a fabric and to form loops thereunder, in combination, a looper movably mounted adjacent said needle and having a rigid shank terminating in a hook adapted to be moved past said needle 65 to intercept said loops, said shank having a shearing edge, a shear member pivotally attached to said looper and cooperative with said shearing edge to sever said loops, a second pivot in said shear member, steps on said looper and adapted to 70 be engaged by said second pivot whereby said shear member may have an arc of swing on said looper determined by the limited distance of movement of said second pivot between said stops, and actuating means attached to said second 75

5 pivot and adapted to move the same back and forth against said stops and through a distance greater than said limited distance whereby said stops, looper and shear may be moved as a unit 5 solely by said actuating means at the end of each swing of said shear.

6 3. In a tufting device, in combination, means to support a fabric, a needle reciprocable to carry 10 a yarn through said fabric and to form loops thereunder, a looper movably mounted adjacent said needle and movable past the same to singly intercept said loops, a shear member movably mounted on said looper and cooperative therewith to shear said loops, stops on said looper to limit 15 the motion of said shear on said looper, and means attached to said shear member to move the same on said looper, said means being operable through said stops to move said looper and shear member as a unit upon completion of each 20 movement of said shear member on said looper.

25 4. In a tufting machine, in combination, a frame, means on said frame to support a fabric, a needle reciprocable through said support to carry yarn through said fabric and adapted to form loops of said yarn thereunder, a bar slidably supported under said frame and reciprocable in a line perpendicular to the path of said needle, said bar having therein a longitudinal slot, a rigid looper secured to said bar and including a shank 30 having a shearing edge and terminating in a hook adapted to pass close to said needle to singly intercept said loops, a shear member pivotally secured to said looper and cooperative with said edge, an extension on said shear member, a pivot 35 in said extension and engaging said slot, said pivot being movable throughout the length of said slot, and means to move said pivot forward a distance greater than the length of the latter's movement in said slot whereby said shear may be actuated to sever a loop on said shank and whereby continuing movement of said pivot may immediately thrust said hook forward to intercept a second loop, the return motion of said moving means being adapted first to open said shear and immediately thereafter to retract said hook.

40 5. The combination claimed in claim 4 wherein said machine comprises a main drive shaft and wherein said moving means includes a rocker shaft supported by said frame, a lever on said rocker shaft, a rod connecting said lever to said pivot, a second lever on said rocker shaft, an eccentric on said drive shaft, and a connecting rod 45 cooperative with said eccentric and articulated to said second lever.

50 6. In a device of the character described, in combination, means to form a series of loops of 55 yarn on a fabric, means movable to individually intercept said loops, means on said intercepting means operable to individually shear said loops, stops on said intercepting means, means attached to said shearing means and adapted to engage said stops to limit the motion of said shearing means on said intercepting means and single means to actuate said shearing means and to move said engaging means against one of said 60 stops whereby a loop on said intercepting means

65 may be sheared and immediately thereafter to move said stop, shearing means and intercepting means as a unit whereby a second loop may be intercepted, said looping means remaining stationary during operation of said shearing means. 5

7. The combination claimed in claim 6, wherein said single means has a return motion adapted to open said shearing means until said engaging means engages said second stop and immediately thereafter to retract said engaging means second 10 stop, shearing means and intercepting means, said intercepting means remaining stationary during opening of said shearing means.

8. In a looper and shear for a tufting machine having a frame carrying a support for a fabric 15 and a needle reciprocable through said support to carry yarn through said fabric and form loops thereunder, in combination, a rigid angle bracket adjustably secured to the bottom of said frame, a vertical key on said bracket, a rear plate having a 20 keyway engaging said key, a horizontal rail on said rear plate, a second horizontal rail on said rear plate above said first rail and vertically spaced thereon, a bar slidably guided between said rails and having a horizontal slot, a cover 25 plate on said rails and retaining said bar in place, said cover plate having therein an opening exposing said slot, vertically adjustable means securing said plates and rails to said bracket, a looper body secured to said bar, a horizontal shank on 30 said body having a downwardly directed shearing edge, a downwardly directed hook on the end of said shank, said hook having a rearwardly inclined rear edge, a shear member pivoted to said body and cooperative with said shearing edge, a blunt 35 nose on said shear cooperative with said inclined edge of said hook to form a V-notch adapted to individually receive said loops, a downward extension on said shear member, a pivot in said extension, said pivot engaging said slot and being 40 adapted to swing freely throughout the length thereof to actuate said shear, and means operable in timed relation with said needle to move said pivot back and forth a distance greater than the length of swing thereof in said slot. 45

9. In a looper and shear for a tufting machine having a frame carrying a support for a fabric and a needle reciprocable through said support to carry yarn through said fabric and to form loops thereunder, in combination, a rigid angle bracket adjustably secured to the bottom of said frame, a vertical key on said bracket, a rear plate having a keyway engaging said key, a horizontal rail on said rear plate, a second horizontal rail on said rear plate above said first rail and vertically spaced therefrom, a bar slidably guided between said rails, a cover plate on said rails and retaining said bar in place, vertically adjustable means securing said plates and rails to said bracket, a looper secured to said body and adapted to intercept said loops when said body is reciprocated between said rails, means on said looper to shear said loops, and means operable in timed relation with said needle to reciprocate said body and to actuate said shearing means. 55 60 65
